Inventor:

Randolph W. Shipley

UNITED STATES PATENT OFFICE.

RANDOLPH W. SHIPLEY, OF DRUMRIGHT, OKLAHOMA.

PIPE-TONGS.

1,209,630.

Specification of Letters Patent.

Patented Dec. 19, 1916.

Application filed September 12, 1916. Serial No. 119,796.

To all whom it may concern:

Be it known that I, RANDOLPH W. SHIPLEY, a citizen of the United States, residing at Drumright, in the county of Creek and

5 State of Oklahoma, have invented an Improvement in Pipe-Tongs, of which the following is a specification.

This invention relates to certain new and useful improvements in pipe tongs and it 10 has for its primary aim to provide a strong and durable tong or wrench of simple construction which will efficiently grip a pipe or other articles arranged within its embrace.

15 Further, the invention resides in the features of construction, arrangements and combinations of parts hereinafter described and claimed, reference being had to the accompanying drawing in which,

20 Figure 1 is a rear elevation of a wrench embodying the present improvements and Fig. 2 is a side elevation thereof.

Referring to like parts by similar characters of reference, the serrated jaw faces 25 A and B have depending stems through which extend transverse securing pins G. The jaw face B is mounted on the forward upper edge of a shank F which is suitably shaped into a handle. The jaw face A is 30 carried on the forward end of a hooked or arc-shaped jaw which has its opposite end bifurcated to straddle the rear upper edge of said shank to which it is pivotally secured by a pin or bolt.

35 An operating lever E is pivoted between its ends to the shank F, one end being formed into a handle and the opposite end being offset to lie in the plane of the web end of the jaw C to which the jaw face A is 40 fixed. The upper end of the operating lever terminates substantially opposite the upper part of the jaw C. A connecting link D joins the operating lever with the jaw C at their upper opposing portions whereby the 45 link is horizontally disposed and transmits the power from the lever to the jaw tangentially of the latter. The pivotal point of the link D on the jaw C is forward of the pivotal mounting of the latter on the 50 shank F so that movement of the jaw is inward or downward. Movement of one jaw face toward the other is limited by the oper-

ating lever coming in contact with the adjacent bifurcation of jaw C.

What I claim is:

1. A pipe wrench comprising a shank having a stationary jaw, a movable jaw pivoted at one end to the shank and having a jaw face on its other end opposing the stationary jaw, an operating lever pivoted between its ends to the shank, said lever having its outer end terminating adjacent the outer end of the movable jaw, and a link arranged transversely of the shank and connecting the said outer end of the lever to the said outer end of the movable jaw to exert a tangential push on said movable jaw. 55

2. Pipe tongs comprising a shank having a fixed jaw on one end, a movable jaw pivoted to the end of said shank adjacent the fixed jaw and provided with a face overhanging and opposing the latter, and an operating lever pivoted to the shank and connected to the movable jaw, the latter serving as a stop for the pivotal movement of 75 the lever.

3. Pipe tongs comprising a shank having a fixed jaw on one end, a movable jaw pivoted to the end of said shank adjacent the fixed jaw and provided with a face overhanging and opposing the latter, an operating lever pivoted to the shank and extended to a point substantially opposite the outer end of the movable jaw whereby a force exerted on the lever will be transmitted substantially tangential to the movable jaw, and a connecting link between the outer end of the movable jaw and said extended end of the lever. 80

4. In a pipe wrench, a shank having a fixed jaw, a movable jaw having a bifurcated part straddling the shank and pivoted thereto, an operating lever pivoted to the shank and having its outer end disposed approximately opposite to the outer end of 95 the movable jaw, and a link connected to the lever and outer end of the movable jaw.

5. In a pipe wrench, a shank having a fixed jaw to grip one face of a pipe, a pivoted jaw connected to said shank to grip 100 the opposite face of the pipe, and means for applying a tangential clamping force to the pivoted jaw at a point including a rigid link disposed at points outwardly beyond and

opposite said second named face of the pipe.

6. A pipe wrench including a shank having a fixed jaw, a curved element pivoted at its inner end to the shank adjacent said fixed jaw and having a jaw at its outer end confronting said fixed jaw, an operating lever pivoted to the shank and having its outer end curved and extending over and beyond the curved element, and a link arranged at 10 substantially right angles to the shank and

pivoted to the extremity of the curved outer end of the lever and the outer end of said curved element.

In witness whereof, I have hereunto affixed my signature in the presence of sub- 15 scribing witnesses.

RANDOLPH W. SHIPLEY.

Witnesses:

W. L. McATEE,
P. A. HARRISON.
